UNITED STATES PATENT OFFICE

162,790

AIRPLANE TOY

William D. Christman, Putnam Valley, N. Y.

Application October 11, 1949, Serial No. 5,421

Term of patent 3½ years

(Cl. D34—15)

To all whom it may concern:

Be it known that I, William D. Christman, a citizen of the United States, residing at R. F. D. #1, Putnam Valley, in the State of New York, have invented a new, original, and ornamental Design for Airplane Toy, of which the following is a specification, reference being had to the accompanying drawing, forming part thereof.

Fig. 1 is a top perspective view of the airplane toy, showing my new design;

Fig. 2 is a rear elevational view thereof; and
Fig. 3 is a side elevational view thereof.

I claim:

The ornamental design for an airplane toy, as shown.

WILLIAM D. CHRISTMAN.
